UNITED STATES PATENT OFFICE

131,643

DESIGN FOR A DRESS ENSEMBLE

William Slepin, Philadelphia, Pa.

Application November 27, 1941, Serial No. 104,352

Term of patent 3½ years

To all whom it may concern:

Be it known that I, William Slepin, a citizen of the United States and a resident of Philadelphia, county of Philadelphia, State of Pennsylvania, have invented a new, original, and ornamental Design for a Dress Ensemble, of which the following is a specification, reference being had to the accompanying drawing, forming a part hereof, wherein:

In the aforesaid figures, the blouse section of the dress is conventionally plain.

The characteristic feature of my design resides in the combination on the ensemble disclosed of the specific jacket member which is trimmed in the manner and position shown.

I claim:

The ornamental design for a dress ensemble, as shown and described.

WILLIAM SLEPIN.
